DUPLICATING APPARATUS

Alfred Marchev, La Grange, Ill., assignor to Dit-
to Incorporated, Chicago, Ill., a corporation of
West Virginia

Application June 26, 1937, Serial No. 150,505

6 Claims. (Cl. 101—132)

The invention relates to duplicating apparatus and has for its primary object the provision of duplicating apparatus which will operate at a relatively high speed.

5 One form of the invention is embodied in a duplicating machine which comprises a rotatable duplicating drum carrying a master from which copies are to be made, the copy sheets being pressed against the master sheet by a plurality of 10 platen rollers. Each platen roller preferably applies all portions of the copy sheet to the master sheet. The force with which the platen rollers press the copy sheets against the master may be 15 adjusted or varied on both rolls simultaneously or the force with which each roll passes the copy sheets against the master sheet may be adjusted individually.

An advantage attending the use of a plurality of platen rollers is that the duplicating machine 20 may be operated at a high rate of speed as each of the platen rollers forces the copy sheets against the master sheet and therefore the copy sheets are in contact with the master sheet twice as long as they would be if a single platen roller were 25 used and the machine operated at the same speed.

Other objects and advantages will become apparent as the following detailed description progresses, reference being had to the accompanying drawings, wherein—

30 Fig. 1 is a vertical longitudinal section taken through a duplicating machine which embodies the invention.

Fig. 2 is an enlarged fragmentary section taken on line 2—2 of Fig. 1.

35 Fig. 3 is a fragmentary section taken on line 3—3 of Fig. 1.

Fig. 4 is a section taken on line 4—4 of Fig. 3.

Fig. 5 is a plan section taken on line 5—5 of Fig. 1.

40 Fig. 6 is a section taken on line 6—6 of Fig. 5.

Fig. 7 is a section taken on line 7—7 of Fig. 6.

Fig. 8 is a section taken on line 8—8 of Fig. 6, and

Fig. 9 is a section taken on line 9—9 of Fig. 6.

Referring to the drawings wherein a preferred form of the invention is illustrated, the reference character 10 designates generally the frame of the improved duplicating machine. Rotatably mounted in the frame 10 is a printing or duplicating drum 11 which is constrained to rotate with a gear 12. A pinion 13, which meshes with the gear 12, is fixed to a shaft 14 rotatably journaled in the frame 10. The shaft 14 has a crank lever 15 pinned thereto. Obviously, when the crank

lever 15 is rotated, the duplicating drum 11 will also rotate.

The machine is provided with a table 16 adapted to receive a stack of copy sheets which may be advanced one by one to a pair of combined feeding and moistening rollers 17 and 18. The roller 17 is contacted by a strip of felt 20 which projects from a container 21 adapted to hold a supply of solvent. When the copy sheets (not shown) pass between the rollers 17 and 18, 10 the upper surfaces of the copy sheets are moistened with the solvent by the roller 17 which obtains the solvent from the felt 20.

The drum 11 is provided with a plurality of gripper units 25 adapted to clamp a master sheet 15 26 upon the drum.

Constrained to rotate with the drum 11 is a large gear 28 which meshes with an idler pinion 29. The idler pinion 29 meshes with a pinion 30 with which the roller 17 is constrained to rotate. 20 The roller 18 is driven by reason of its frictional engagement with the roller 17.

The master sheets have the data to be duplicated written or typewritten thereon in reverse so that when a portion of the carbon or ink is 25 dissolved and transferred to the moistened surface of the copy sheet, it will appear in correct, readable form. The solvent on the copy sheets is applied, of course, to the carbon or ink on the master sheet and dissolves it gradually. 30

It will be noted that the roller 18 is mounted on a shaft 35 which has its ends supported by levers 36 pivoted upon pins 37 projecting from the frame. Springs 39 engage toothed ends of the levers 36 and yieldingly urge the roller 18 toward 35 the roller 17.

It may be mentioned that the container 21 is supplied with solvent from a larger container 40 by means which do not form a part of this invention. 40

A pair of platen rollers 41 and 42 cooperate with the drum 11 to press the copy sheets against the master sheet 26. The rollers 41 and 42 are preferably formed from rubber and are preferably mounted upon shafts 43 and 44, respectively. 45 The shafts 43 and 44 are mounted in means comprising a pair of levers 45 which are pivoted upon pins 46 mounted in the frame 10. The levers 45 are pivoted intermediate their ends and each lever comprises a downwardly extending arm 45a 50 through which a set screw 47 is screw-threaded. Nuts 48 upon each set screw 47 are adapted to lock the set screw in adjusted positions relative to the arm 45a. The head of each set screw 47 rides upon an eccentric 50 fixed to a shaft 51 which is 55

rotatably journalled in the frame 10. A knob 53, shown in dotted lines in Fig. 1, is mounted upon one end of the shaft 51 and may be rotated by the operator to rotate the shaft 51 and the eccentrics 50. The eccentrics 50 may be rotated to displace the levers 45a in a clockwise direction (Fig. 1) to increase the force with which the platen rollers 41 and 42 press copy sheets against the master sheet 26. Also, if it is so desired, the eccentrics 50 may be rotated to diminish the force with which the platen rollers 41 and 42 will press copy sheets against the master sheet 26. The ends of the shaft 43 are mounted in ball bearings 55 which simply rest in semi-circular notches 56 formed in the upper ends of the levers 45. A set screws 57 screw-threaded through lugs 58 and 59 formed integral with the levers 45 support the ball bearings 55 and may be manipulated to raise or lower the ball bearings so as to vary the force with which the roller 41 will press copy sheets against the master sheet 26.

The shaft 44 has its ends mounted in ball bearings 60 which, in turn, are mounted in collars 61 being seated in recesses 63 formed in cap members 65 and 66. The cap member 65 has a slot 68 extending diametrically of it in its outer end surface. Riding in the slot 68 is a tongue or lug 69 formed on a pin 70 which is provided with a knurled knob 71 which may be rotated by the operator to rotate the pin 70. A collar 73 formed integral with the pin 70, is adapted to abut against the outer slotted end surface of the cap 65. A compression spring 74 disposed around the pin 70 is interposed between the collar 73 and a washer 75 which bears against an inner surface of the frame 10. (Fig. 6.) Obviously, the spring 74 yieldingly urges the pin 70 to the right (Fig. 6) to hold the collar 73 against the outer end surface of the cap member 40 65.

Extending through a bore 80 formed in the knob 71 is a pin 82 provided with an integral collar 83 which normally abuts against a shoulder 84 formed in the bore 80. The outer end of the bore 80 is closed by a bushing 86 which has a hole through it to accommodate the pin 82. A compression spring 87 disposed around the pin 82 and interposed between the bushing 86 and the collar 83 yieldingly urges the pin 82 to the right (Fig. 6) so that the right hand end (Fig. 6) of the pin 82 will normally engage one of a plurality of holes 90 formed in a plate 91 which is secured to the frame 10 by screws 92 (Fig. 7). It will be noted that the holes 90 are of such size and are spaced in such manner that they open into each other so that while they are not really separate holes, they serve in the same manner as if they were separate holes. When the pin 82 engages one of the holes 90, it holds the knob 71 against rotation. The pin 82 is provided with a knurled head 94 whereby the pin may be displaced longitudinally against the action of the spring 87 to disengage the pin from one of the holes 90.

It will be noted that the pin 70 extends through an arcuate slot 97 provided in the plate 91 and it also extends through a corresponding arcuate slot 98 formed in the frame 10.

As best shown in Figs. 6, 8 and 9, the axis of rotation of the platen roller 42 is eccentric with respect to the longitudinal axis of the cap member 65, the longitudinal axis of the cap member 65 being also its axis of rotation. The cylindrical surface of the recess 63 has its longitudinal axis co-incident with the axis of rotation of the roller 75 42 and therefore the cylindrical surface of the

recess 63 is eccentric with respect to the axis of rotation of the cap member 65.

The cap member 66 is identical in construction with the cap member 65 except for the fact that it does not have a slot 68. The cap members 65 and 66 ride in semi-circular notches 45b provided in the upper ends of the levers 45. A bar 100 extends between and is secured to the cap members 65 and 66, the construction being such that when the cap member 65 is rotated in its arcuate notch 45b, of the associated lever 45, the cap member 66 will rotate in unison through the same angular distance. It will be readily understood that if the pin 82 is withdrawn from engagement with one of the holes 90 and the knob 71 is rotated, the cap member 65 will also rotate and will cause the roller 42 to move towards or away from the drum 11, the direction in which the roller 42 is displaced being dependent upon the direction in which the knob 71 is rotated. Such adjustment permits one to vary or adjust the force with which the platen roller 42 applies the copy sheets to the master sheet 26. Obviously, if it is so desired, the platen roller 42 may be brought into a position wherein it does not co-operate with the drum 11 and all of the duplicating work may be done by the drum 11 and the platen roller 41. Likewise, the platen roller 41 may be rendered functionally inoperative so that all the work can be done by the roller 42. 30

When a duplicating machine of the kind described is in operation, but is provided with only one platen roller, the speed at which the machine can be operated is oftentimes limited by the necessity for running it slow enough so that each copy sheet will remain in contact with the master sheet a sufficient length of time to obtain a good copy of the data on the master sheet. Of course, the copy sheets are being advanced between the drum 11 and the single platen roller but unless 40 they operate slow enough, poor copies will be the result. By using two platen rollers, the speed of the machine can be increased materially and there is considerable saving of time.

Pivoted upon the pins 31 are a pair of levers 45 105 which have semi-circular notches 106 which rotatably journal the ends of a shaft 107 which carries the felt roller 108. Both of the levers 105 are provided with notched ends 109, one of the notches in each end being engaged by a spring 110 which yieldingly urges the roller 108 in a counter-clockwise direction (Fig. 4) around the pins 31 so that the roller 108 contacts the roller 18 and absorbs excess solvent that accumulates on the roller 18. The other end of each spring 110 is fixed to a pin (not shown) projecting from the frame 10. The force with which the felt roller 108 bears against the roller 18 may be varied by hooking the springs 110 in other notches of the notched ends 109. 60

The roller 17 is preferably formed from non-absorbent material, the roller 18 preferably being formed of absorbent material.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

I claim:

1. In a duplicating machine, the combination 75

of a frame, a duplicating drum rotatably mounted in the frame, means for driving said drum, means for mounting a master sheet on said drum so as to revolve therewith, a support adjacent to the drum along which a copy sheet may be moved to the drum, and a plurality of platen rollers in spaced relation to each other about the drum adapted to press copy sheets against said master sheet at a plurality of points across the sheets when such copy sheets are fed from the support between the drum and one of said platen rollers.

2. In a duplicating machine, the combination of a frame, a duplicating drum rotatably mounted in the frame, means for driving said drum, means for mounting a master sheet on said drum so as to revolve therewith, a table adjacent to said drum along which a copy sheet may be moved to the drum, two levers pivotally mounted on a horizontal axis on said frame at opposite ends of said drum, a platen roller journaled in said levers between said axis and the drum in position to engage the drum, a second platen roller journaled in said levers in spaced relation to said first named platen roller circumferentially of the drum, means for swinging said levers in unison for moving said platen rollers toward and from said drum, and means for adjusting said platen rollers with respect to said levers for bringing said rollers into substantially even pressure relationship to said drum.

3. In a duplicating machine, the combination of a frame, a duplicating drum rotatably mounted in the frame, means for driving said drum, means for mounting a master sheet on said drum so as to revolve therewith, a table adjacent to said drum along which a copy sheet may be moved to the drum, two supporting members movably mounted in position at opposite ends of said drum, a platen roller rotatably mounted on said supporting members, a second platen roller, means comprising eccentric bearing members for mounting said second roller on said supporting members, means for causing said eccentric bearing members to rotate in unison, one of said eccentric bearing members being provided with a groove across its face, a pin rotatably mounted in position in engagement with said groove for rotating said eccentric bearing members, and means for locking said pin against rotary movement.

4. In a duplicating machine, the combination of a frame, a duplicating drum rotatably mounted in the frame, means for driving said drum, means for mounting a master sheet on said drum so as to revolve therewith, a table adjacent to said drum along which a copy sheet may be moved to the drum, two supporting members movably mounted in position at opposite ends of said drum, a platen roller rotatably mounted on said supporting members, a second platen roller, means comprising eccentric bearing members for mounting said second roller on said supporting members, means for causing said eccentric bear-

ing members to rotate in unison, one of said eccentric bearing members being provided with a groove across its face, a pin rotatably mounted in position in engagement with said groove for rotating said eccentric bearing members, a head 5 mounted on said pin for rotating the pin, and a detent yieldingly mounted in said head in position to engage any of a plurality of openings in the frame for locking said pin against rotary movement from the desired adjusted position. 10

5. In a duplicating machine, the combination of a frame, a duplicating drum rotatably mounted in the frame, means for driving said drum, means for mounting a master sheet on said drum so as to revolve therewith, a support adjacent to the drum along which a copy sheet may be moved to the drum, two supporting members movably mounted in position at opposite ends of said drum, a platen roller rotatably mounted on said supporting members, a second platen roller, 15 means comprising eccentric bearing members for mounting said second roller on said supporting members, means connecting said bearing members together whereby a rotary adjustment of one causes a corresponding adjustment of the other, 20 a pin rotatably and slidably mounted in the frame opposite one of said bearing members so as to have transversely adjustable engagement with said bearing member for rotating it and so as to be movable longitudinally out of engagement with the bearing member, and means for holding said pin releasably against rotary movement for maintaining said second platen roller 25 in its adjusted position.

6. In a duplicating machine, the combination of a frame, a duplicating drum rotatably mounted in the frame, means for driving said drum, means for mounting a master sheet on said drum so as to revolve therewith, a support adjacent to the drum along which a copy sheet may be moved to the drum, two supporting members movably mounted in position at opposite ends of said drum, a platen roller rotatably mounted on said supporting members, eccentric bearing members rotatably mounted in notches in said 35 supporting members, a second platen roller rotatably mounted in said eccentric bearing members so as to be movable toward and from said drum, a crossbar connecting said eccentric bearing members together whereby a rotary adjustment of one causes a corresponding adjustment of the other, a pin rotatably and slidably mounted in the frame opposite one of said eccentric bearing members so as to have transversely adjustable engagement with said bearing member for rotating it and so as to be movable longitudinally out of engagement with the bearing member, yielding means normally holding said pin in engagement with said eccentric bearing member, and means for holding said pin releasably against rotary movement for maintaining 40 said second platen roller in its adjusted position. 45

ALFRED MARCHEV.
